2 SHEETS—SHEET 2.

UNITED STATES PATENT OFFICE.

CLINTON BOWEN, OF FOSTORIA, OHIO.

POST-ANCHOR.

1,015,611.

Specification of Letters Patent. Patented Jan. 23, 1912.

Application filed July 15, 1910. Serial No. 572,120.

To all whom it may concern:

Be it known that I, CLINTON BOWEN, a citizen of the United States, residing at Fostoria, in the county of Seneca and State 5 of Ohio, have invented certain new and useful Improvements in Post-Anchors, of which the following is a specification.

This invention relates to fences, and more particularly to post anchors, and has for its 10 object to provide an anchor by means of which a post may be so braced and guyed as to hold it upright in the ground, against the tension of a wire fence, or the weight of a wooden or metal fence.

15 While a number of anchors of this character have been patented, and it is therefore not my desire to claim the broad idea of an anchor of this character, nevertheless, there have been inherent shortcomings in the anchors introduced to the public, which it is 20 an object of my invention to overcome.

I refer particularly to structures in which the fins which bite into the earth are held in a positive predetermined position, and 25 which are therefore such that, should one of the fins engage a stone or other obstruction, the operation of the anchor would be seriously interfered with.

A special object of my invention is, therefore, 30 to provide an anchor in which the engaging fins are free to rotate until they have bitten into the earth a proper distance, when they will be forced into position to securely fasten the anchor.

35 Another object is to provide a post anchor which may be manufactured at a low figure, and in which the fins may be made from cheap material.

Other objects and advantages will be apparent 40 from the following description, and it will be understood that changes in the specific structures shown and described, may be made within the scope of the claims without departing from the spirit of the invention.

In the drawings forming a portion of 45 this specification, and in which like numerals of reference indicate similar parts of the several views,—Figure 1 is a side elevation of a three fin anchor, the fins being in expanded position. Fig. 2 is a bottom plan of a three fin anchor. Fig. 3 is a side elevation of a three fin anchor, the fins being in folded position. Fig. 4 is a 50 detail perspective view of one of the fins. Fig. 5 is a view showing a two fin anchor

in elevation, partly broken away to disclose the structure of the follower. Fig. 6 is a longitudinal section through one of the anchors. Fig. 7 is a detail view in section 60 showing the arrangement of the follower head in the modified form.

Referring now to the drawings, there is shown a post anchor which consists of a threaded rod 10, having an eye 11 formed 65 at its upper end, for the reception of the lower end of a guy wire 12. At its lower end, the rod 10 has engaged therewith a nut 13, which is fastened immovably thereupon by means of a transverse pin 14.

70 Loosely mounted upon the rod above the nut, there is a concavo-convex spreader plate 15, which has its convex surface directed downwardly, and which has a central opening 16 receiving the rod. This 75 spreader plate, is circular, as shown, and has secured thereacross at its concave surface, a transverse diametrically disposed plate 17, which has its ends engaged in notches 18 formed in the edge portion of 80 the plate. The upper surface of the plate 17 is thus flush with the peripheral edges of the spreader plate, as shown.

The plate 17 has a central opening 19, which receives the rod 10, and loosely engaged upon the rod above the plate 17, there is a pipe sleeve 20, of the usual character, which is slidable and revoluble upon the rod. If desired, any suitable sleeve may be used in this position in place of an interiorly threaded sleeve, but interiorly threaded sleeves are used in the manufacture of 90 the anchor, being standard fitting.

A follower head 21 is engaged with the thread of the rod 10 above the sleeve 20, this 95 follower head having a central interiorly threaded passage 22, receiving the rod, and a plurality of radially extending bracket portions 23, each including two spaced walls 24, and a connecting top portion 25. Between the walls 24 of each of these bracket members, there is pivoted a ground engaging fin 26, this fin being movable, in each instance, in the vertical plane of the rod 10, as shown. When the follower head 21 is 105 a considerable distance from the spreader plate 15, the fins 26 may extend downwardly against the rod, but, as will be seen, the rod may be rotated to cause the follower head to move downwardly thereon, and 110 bring the under faces of the fins into contact with the upwardly directed edge of the

spreader plate 15, when the free ends of the fins will be directed outwardly and brought into engagement with the walls of the hole in which the anchor is of course placed, 5 and forced into the earth surrounding the hole. The sleeve 20 acts as a stop for the follower head to prevent downward motion thereof to such an extent as to jam the parts and render difficult the removal of 10 the anchor when desired, as will be understood.

Each of the fins 26, as shown in the drawings, consists of a metallic plate, somewhat elongated, and having a sharpened edge A 15 at one end, the plates being given a transverse curvature throughout their entire length, and at their ends opposite to the edges A, the side portions of the plates are folded against each other to produce stem 20 portions B, which extend at right angles to the major transverse dimension of the plate, and which provide, thus, thickened stems which are engaged between the walls 24 and have passed therethrough pivot pins 27 25 as illustrated.

In Fig. 5 there is shown a two fin anchor, in which the follower head consists of a metallic plate bent longitudinally to bring its side portions into parallel relation, these 30 side portions being connected by an upper bight portion C, having an inner transverse dimension less than the diameter of the rod 10. A hole sufficiently large to receive the rod is formed through the bight C, as 35 indicated at D, and this hole is threaded, the threads being also cut in the inner surfaces of the side portions 24 of this follower head so as to give a long bearing for the rod.

40 What is claimed is:

1. A post anchor comprising a concavo-convex plate having a central opening, a diametrical plate secured across the concave side of the first named plate, said diametrical plate having an opening alining with the opening of the first named plate, a 45 threaded rod engaged through the two openings, a confining nut engaged with the rod below the convex side of the first named plate, a sleeve loosely mounted upon the 50 rod and resting upon the diametrical plate,

a follower head threaded upon the rod above the sleeve, said follower including a plurality of spaced ears, and fins pivoted at their inner ends between the ears, said fins 55 having arcuate under surfaces arranged to engage against the edge of the concavo-convex plate for outward movement of the fins when the follower head is moved in the direction of the sleeve, said sleeve being arranged to receive the follower head thereagainst to limit the movement thereof.

2. A post anchor including a threaded rod, and a follower head mounted upon the rod, said follower head being formed of a 60 metallic plate bent upon itself to produce spaced side portions and a connecting bight, the space between the side portions being less than the transverse dimension of the threaded rod, said bight having an opening formed therethrough, said opening and the inner faces of the walls being threaded for engagement with the threaded rod.

3. A post anchor comprising a concavo-convex plate having a central opening, a 75 diametrical plate secured across the convex side of the first named plate, said diametrical plate having an opening alining with the opening of the first named plate, a threaded rod engaged through the two 80 openings, means for holding the threaded rod against withdrawal from the openings, said means being engaged with the threaded rod at the convex side of the plate, a follower head threaded upon the rod above 85 the sleeve, said follower including a plurality of spaced ears, and fins pivoted at their inner ends between the ears, said fins having arcuate under surfaces arranged to engage against the edge of the concavo-convex plate, 90 for outward movement of the fins when the follower head is moved in the direction of the concavo-convex plate, said threaded rod being rotatable with respect to said plate to move the follower head thereupon. 95

In testimony whereof I affix my signature, in the presence of two witnesses.

CLINTON BOWEN.
